3 SHEETS—SHEET 3.

UNITED STATES PATENT OFFICE.

PETER HOITSMA, OF PATERSON, NEW JERSEY.

SCAFFOLD MACHINE.

1,416,296.

Specification of Letters Patent. Patented May 16, 1922.

Application filed February 14, 1921. Serial No. 444,650.

To all whom it may concern:

Be it known that I, PETER HOITSMA, a citizen of the United States, residing at Paterson, in the county of Passaic and State 5 of New Jersey, have invented certain new and useful Improvements in Scaffold Machines, of which the following is a specification.

This invention relates to scaffolding apparatus, and particularly to apparatus whereby, given suitable uprights spaced apart and from the front of a building or the like, the workers on the scaffold can from time to time raise or lower the platform on 10 which they work, on said uprights as supports without leaving the platform. According to my invention, there will be two climbing and supporting means or machines on the respective supports, the two machines 15 being practically alike and together supporting the planking or equivalent platform, the invention consisting in the novel construction and arrangement of the parts of such a machine whereby the operations of raising 20 and lowering can be easily and readily accomplished, the elements of safety and reliability are assured, and the machine is simple and inexpensive.

Figure 1 in the accompanying drawings 30 shows a scaffold apparatus in front elevation embodying my invention;

Figure 2 is a side elevation;

Figure 3 is a vertical sectional view of one 35 of the machines in place on its upright, the parts being in the positions they occupy at a time when the machine is undergoing lifting;

Figure 4 is a view similar to Figure 3, but showing the parts in the position they occupy 40 when the machine grips the upright and is stationary;

Figure 5 is a plan view of the machine, partly in section, omitting the means thereof for supporting the platform;

Figures 6 and 7 are sectional views on the 45 lines 6-6 and 7-7, respectively, of Figures 3 and 4;

Figure 8 is a side elevation, partly in section, and on a larger scale than Figure 2; 50 and

Figure 9 shows in plan a brace for the uprights.

a in Figure 2 designates the front of a building, and *b* spaced uprights which will 55 rest on the ground and will preferably consist of wooden lengths (as 2 x 4s) and will

further be progressively extended upward to any desired height by lap-jointing or otherwise joining the ends of said lengths, the uprights being secured to the building at 60 successive elevations by braces, such as *c*, shown in Figures 1, 2 and 9; it will be understood that when in climbing with the use of my apparatus a machine is to pass a brace *c* above it, upon the machine having nearly 65 reached said brace another such brace will be first arranged immediately below the machine to permit the removal of the first brace.

Two shoe structures, adapted to bear against opposite sides of each upright *b* and 70 pivotally connected by linking means, are provided, one being adapted to assume the downward pressure of the planking or other platform and the other to grip the upright, their coaction to insure the grip being due 75 to the linking means. These shoe structures are generally designated by the characters *A* and *B*. The shoe structure *A* consists of two vertical plates *d*; sleeves *e* spacing them at top and bottom; a long bar *f* extending 80 through the plates and the upper sleeve; a bolt *g* having a nut *g'* and penetrating the plates and the lower sleeve; sleeves *h* on the free or projecting ends of the bars *f*; nuts *f'* on the ends of the bar; and braces *i* connecting the bolt *g* and bar *f* (being penetrated by them), the nuts *g'* and *f'* being adapted 85 to be screwed up to clamp the several parts mentioned tight and form a rigid structure.

Otherwise stated, each shoe *A* has opposite 90 projecting brackets (formed by *f*, *h*, *i*), and on these the ends of the planking *j* to form the platform (or rather two platforms, one

inward and the other outward of the uprights *b*) is supported. The other shoe *B* is 95 a plate *k* which preferably has each end sharpened so as to grip the wood of the upright.

The linking means in the present case includes two parallel pairs of links *l* pivoted on bolts *m* in the plates *d* of shoe *A* 100 and the plate *k* of shoe *B*, being properly spaced by sleeves *n* on the one hand and the plate *k* on the other. It will be seen that

the parts *A*, *B*, *l* form a parallel lever system where, as in the present case, there are 105 two, upper and lower, linking means, which is the preferred construction; and in this the preferred construction I find it best to allow collapsing movement of the lever system only in that way which involves movement of shoe 110 *A* downwardly or shoe *B* upwardly, and not in the opposite direction (the reason for

which will appear later), and to that end I 5 fulcrum on a bolt o in shoe A a lever p which is substantially U-shaped in side elevation (Figure 8) and has a long operating arm and a short power-arm, the latter being pivoted at q to a linking means, here formed by two links r , which is in turn connected with a suitable pivot, as m , on shoe B, so that the lever system is capable of collapsing 10 movement only in such way that A can move relatively downward and B relatively upward: compare Figure 3, showing points o , q and m alined, so that the collapse can take place only as just stated, with Figure 4, 15 showing lever p swung downward and the lever system collapsed and thus gripping the upright. For holding lever p in the position shown in Figure 4 I provide it and shoe A with holes adapted to receive a pin s , as 20 an ordinary nail; it will be observed that the members p r afford means for exerting collapsing pressure on the lever system so as to cause the shoes to grip the upright, the grip thus additionally obtained being maintained upon inserting the pin s in lever p 25 and shoe A.

Shoe B is equipped with a pivoted dog t having a long outer arm and a short inner arm, the latter being pointed and reaching 30 downward and adapted to bear against the upright and catch therein.

Once the shoe B obtains a grip on the upright, as by its points catching in the same, the grip is perfected by the weight of the 35 shoe A and the load it carries, the effect being to collapse the lever system and increase the pressure of B (and consequently the hold which its points obtain) on the upright, as well as the frictional pressure of A thereon. 40 The pressure thus obtained, if desired, for the sake of additional safety, can be increased as explained by forcing and locking down lever p .

Each machine includes a lifting means 45 connected with its lever system and adapted to assume a shifting purchase on the upright. To this end u is a lever that is fulcrumed in a block v and is connected with the shoe A by links w , the block being 50 adapted to bear against a face of the upright. Pivoted to the block one above the other are two shackles x and y , each being substantially U-shaped in plan and straddling the upright. When the operator elevates the handle or free end of the lever u 55 the result is to shift the block v upwardly along the upright, link w acting as a fulcrum; the shackles are at this time kept from binding on the upright by the operator's free hand. When the lever is now to be depressed to effect the lifting, shackle x is raised to bind against the upright and prevent the block tilting on its lower corner. Sometimes in descending with the machine the gripping 60 means may catch on an obstruction on the 65

upright (as a nail left therein), so that power would have to be applied to the lever to overcome the obstruction and positively force down the gripping means (which, as will appear, is then rendered ineffective to grip); at this time shackle y is allowed to fall and so by purchase obtained on the upright keep the block from tilting on its upper right-hand corner. 70

The gripper formed by shoes A and B is 75 one which grips the upright under load but moves freely upward on the upright when lifted. That is, once shoe B obtains an effective hold the pressure of the load on shoe A results in the shoes coacting to exert clamping pressure on the upright. The initial grip of B on the upright when A is free of the lifting force is rendered certain by the dog t , which bites or catches in the upright 80 however far B may perchance be spaced 85 from the upright.

When the lifting means comprising lever u and its adjuncts is operated (p being unlocked) each lifting movement thereof obviously results in opening or releasing movement of the gripper or gripping means; the pivot o being outward of a vertical line through q , shoe A is shifted upwardly relatively to shoe B, lever p swinging to the position of Figure 3 and shoe B being prevented 90 from movement downward past its position there shown by $p-r$. When the new position of the gripper has been attained the gripper assumes a fresh grip. 95

Dog t is not indispensable, but it insures 100 certainty and also promptness of the gripping action once the weight of shoe A and its load is free to act.

If the dog be held in inactive position and lever p held up (Figure 3) the gripper 105 is ineffective to clamp the upright. For descending, therefore, the operator can utilize the lifting means to controllably lower the gripper step by step, lever p being held up during each downward movement and at the 110 end thereof pressed downward to cause the clamping of the upright until a fresh purchase can be taken on the upright by the lifter for the next downward movement; or dog t and said lever can simply be allowed 115 to fall to cause the new purchase.

A pair of slings z can be suspended from the projecting brackets of the two machines to support a cross-piece 2, the cross-pieces serving to support material 3 used in the 120 building construction.

Having thus fully described my invention, what I claim is:—

1. A scaffold machine adapted to be shifted vertically on a suitable upright and including a load-carrying member adapted to bear against one face of the upright, a gripping member adapted to grip the opposite face of the upright, and linking means extending from one member across the upright 125 130

to the other member and pivotally connecting said members.

2. A scaffold machine adapted to be shifted vertically on a suitable upright and including a load-carrying member adapted to bear against one face of the upright, a gripping member adapted to grip the opposite face of the upright, linking means extending from one member across the upright to the other member and pivotally connecting said members, and means to move one of said members toward and from the other.

3. A scaffold machine adapted to be shifted vertically on a suitable upright including a gripping member adapted to grip one face of the upright, a load-carrying member adapted to bear against an opposite face of the upright at a point opposite the gripping member, and means, connecting said members, to move one toward and from the other.

4. A scaffold machine adapted to be shifted vertically on a suitable upright including a gripping member adapted to grip one face of the upright, a load-carrying member adapted to bear against an opposite face of the upright at a point opposite the gripping member, and a lever and a link pivoted one to one member and the other to the other and also pivotally connected together.

5. A scaffold machine adapted to be shifted vertically on a suitable upright and including a load-carrying member adapted to bear against one face of the upright, a gripping member adapted to grip the opposite face of the upright, linking means extending from one member across the upright to the other member and pivotally connecting said members, and means to move one of said members toward and from the other including a lever pivoted to one member and operatively connected to the other.

6. A scaffold machine adapted to be shifted vertically on a suitable upright and including a load-carrying member adapted to bear against one face of the upright, a gripping member adapted to grip the opposite face of the upright, linking means extending from one member across the upright to the other member and pivotally connecting said members, and means, connecting said members, to limit the downward movement of the gripping member relatively to the other member.

7. A scaffold machine adapted to be shifted vertically on a suitable upright and including a load-carrying member adapted to bear

against one face of the upright, a gripping member adapted to grip the opposite face of the upright, linking means extending from one member across the upright to the other member and pivotally connecting said members, and a lifting means operatively connected with the load-carrying member and having vertically shiftable means to grip the upright.

8. In a climbing scaffold apparatus, the combination of a gripping means including a gripping member adapted to grip one face of the upright to be climbed and a load-carrying member coupled with the gripping member for up and down movement relatively thereto and away from and also against an opposite face of the upright, and a lifting means including a lever operatively connected with the load-carrying member and a fulcrum-support for the lever shiftable on and adapted to grip the upright.

9. A scaffold machine adapted to be shifted vertically on a suitable upright and including a load-carrying member adapted to bear against one face of the upright, a gripping member adapted to grip the opposite face of the upright, linking means extending from one member across the upright to the other member and pivotally connecting said members, and a lifting means adapted to be operatively connected with the upright and having lifting connection with the load-carrying member.

10. In a climbing apparatus, the combination of a gripping means adapted to grip and thereby secure itself to the upright to be climbed on downward movement of said means but slidably upwardly free of said upright, and lifting means including a block to bear against a face of the upright, a shackle pivoted to the block and embracing and adapted to bear against the other face of the upright, a lever fulcrumed in the block and a link connecting the lever and lifting means.

11. In a scaffold machine, the combination, with a gripping system including members to grip opposite faces of the uprights to be climbed and arranged opposite each other and a linking member pivotally connecting them, of means, connecting two of said members, to move the first two members toward and from each other.

In testimony whereof I affix my signature.

PETER HOITSMA.
